UNITED STATES PATENT OFFICE.

ELMER P. SACREY, OF PHILADELPHIA, PENNSYLVANIA.

GRINDING-MACHINES

1,233,608.

Specification of Letters Patent. Patented July 17, 1917.

Application filed March 30, 1916. Serial No. 87,685.

To all whom it may concern:

Be it known that I, ELMER P. SACREY, a citizen of the United States, and resident of Philadelphia, county of Philadelphia, and 5 State of Pennsylvania, have invented an Improvement in Grinding-Machines, of which the following is a specification.

The object of my invention is to provide a construction of grinding machine suitable 10 for effectively and rapidly grinding articles according to pattern, whereby the work may be accurately done and at a cost greatly lower than is possible where hand manipulation of the work alone is employed.

A further object of the invention is to enable the machine to be adjusted to present the grinding wheel at any angle to the work, and to maintain said angle during the transverse movement of the work relative to the 20 wheel and while the coaction between the holder for the grinding wheel and holder for the work is controlled by use of a pattern.

My object is further, to provide an adjustable templet, set in respect to a definite pattern carried on the machine and by means of which adjustable templet the work may be set so to be properly clamped upon the work-holding table, whereby said work 30 will have the desired position to insure grinding under control of the pattern.

A further object is to provide, in a machine of the character above indicated, means by which the coaction between the 35 grinding wheel and work may be such that any definite depth of cut may be inscribed, whereby after the work is set according to templet, the same extent of grinding may be had with each casting, forging or 40 stamping of the same kind.

With the above and other objects in view, the nature of which will be more fully understood from the description hereinafter, the invention consists in the novel construction of grinding machine as hereinafter 45 more fully described and defined in the claims.

Referring to the drawings:—Figure 1 is a side elevation of a grinding machine embodying my invention, with portions thereof broken away; Fig. 2 is a front elevation of the same; Fig. 3 is a sectional view of the clamping means between the base and head; Fig. 4 is a plan view showing the manner 55 of employing the templet in setting the

work to be ground preliminary to clamping it in position; Fig. 5 is an elevation of the templet removed; Fig. 6 is a plan view showing the means for adjusting the work table to insure the degree of cut; Fig. 60 7 is a plan view of my improved machine; and Figs. 8 and 9 are cross sections of the perimeters of the usual shaped grinding wheels employed in machines of this class.

2 is the bed of the machine and may be of any suitable shape, that shown being of 65 pedestal form. Adjustable supported upon the top of the bed 2 is the turret 3, the connection being such that the turret is capable of swinging about a vertical axis. The extent of the adjustment of the turret may be indicated by a scale 14; and it may be clamped in the position of adjustment by the central bolt 13 carried by the base of the turret and drawn down by the transversely 70 arranged eccentric shaft 10 in the bed adapted to be operated by the lever 11. When the parts are in the position shown, the turret is fixedly clamped upon the bed. The nuts 13 on the bolt 12 may be adjusted 75 to compensate for wear and to insure that the clamping action shall be sufficient for the purpose.

The turret 3 may be provided with a handle 3^a, if so desired, to facilitate its adjustment on the bed; and is provided with a sliding-head 4 carrying the bearings 7 in which the shaft 9 of the grinding wheel 6 is journaled, said shaft being provided with the belt wheel 8 arranged between the bearings, as shown. The shapes of the grinding wheels at the perimeters suitable for a machine of this character are indicated in Figs. 8 and 9. The head is adjustably supported upon the turret by a longitudinal guide 5, 80 very similar to what is employed in lathes; and this guide is arranged transversely to the axis of the shaft 9 of the grinding wheel, so that the grinding wheel may be shifted in the plane of its rotation. The 85 head 4 may be reciprocated by any suitable hand-operated means, that shown, by way of example, being a rach 15 secured to the head and a gear segment 16 adapted to be rocked by the handle 17, as will be understood by reference to Fig. 1. By oscillating the handle 17, the head 4 and its grinding wheel 6 may be shifted horizontally, so that the latter is moved to and from the work, indicated at 28; the extent of the per- 90 95 100 105 110

missible movement toward the work being regulated by the traversing arm 38 and the pattern 37, as hereinafter more fully described. The traversing arm 38 is horizontally guided upon the head 4 and adjustably clamped in position by the clamp 40.

The base 2 of the machine is provided with a laterally extending guide frame 18 having one or more adjustable clamps 21 which may consist of slotted portions 21^a to one of which is attached a screw bolt 21^b upon which the hub of a handle 21^c is screwed as a nut. By throwing the handles upward, the split portions 21^a are forced 10 toward each other so that the guide frame 18 is adapted to clamp the downwardly extending part 19 of the adjustable bed 20. This part 19 is provided with a rack 48 with which a pinion 49 meshes, said pinion 20 adapted to be rotated by a hand lever 50 journaled to the guide frame 18. The hand lever 50 is provided with a detent 52 which engages holes in a locking segment 51 on the side of the guide frame 18, as clearly 25 shown in Figs. 1 and 2. In the position in which the parts are shown, the head 20 is in its lowermost position; and as the hand lever 50 is moved to the right (Fig. 1), the head 20 will be raised to the desired position and 30 may then be first locked by the detent 52 and subsequently clamped rigidly by means of the clamps 21 so as to take the strain off the detent 52.

The head 20 is formed with dove-tailed 35 guides 23 arranged transversely to the plane of the grinding wheel, and supported upon this head 20 and its guides 23 is arranged the slide frame 22. The slide frame 22 is provided with a lower table 35 upon which 40 the pattern 37 is clamped by the clamping devices 36, said pattern being positioned to cooperate with the traversing arm 38, as before explained. The slide 22 is further provided with upwardly extending arms 24 45 which are joined in an auxiliary guide head 25 having dove-tailed guides 29 arranged at right angles to the guides 23. Supported by and guided upon the supplemental guide head 25 and its guides 29, is the work-table 50 33 upon which the work 28 is clamped by means of the clamping devices 27. It is thus seen that the table 35 for the pattern and the table 26 for the work are arranged at different elevations, the former adapted 55 for cooperation with the traversing arm 38 and the latter for cooperation with the grinding wheel 6, the action of the latter upon the work being controlled and governed by the cooperation of the traversing arm 38 with the pattern 37. As the slide frame 4 is movable to and from the pattern table 35 and the work-table 26, it is manifest that the grinding wheel 6 is permitted to grind the work to any depth which is 60 permitted by the traverse arm 38 in its con-

tact with the pattern 37. It will also be seen that if the slide frame 22 is adjustably moved along the guides 23 of the head 20, the work and pattern will be respectively given a traversing movement with respect 70 to the grinding wheel 6 to the traverse arm 38; and if at the time that this is done, the handle 17 is moved to press the traverse arm 38 in contact with the transversely moving pattern 37, the grinding wheel 6 will be shifted toward and from the work 28 in accordance with the dictates of the pattern, and as the work is simultaneously moved transversely at the same rate as the movement of the pattern, the grinding performed 80 on the work will bring the said work to the shape of the pattern. The slide frame 22 may be shifted upon the head 20 by any suitable means such as employed in lathes, but I prefer a construction such as is illustrated and which comprises a suitable rack 41 secured to the slide frame 22 and engaged by a pinion 42 secured upon the upper end of the shaft 43 journaled in the head 20, and which shaft may be rotated by hand control. 90 In the particular mechanism shown, the shaft 43 is provided with a worm wheel 44, and said worm wheel is rotated by means of a worm 45 secured to a horizontal shaft 46 having a hand wheel 47. By rotating the hand wheel 47 in one direction or the other, the slide frame 22 may be shifted upon the head 20, as above described. Any other suitable means for shifting this slide frame 22 may be employed if so desired, and I therefore do not restrict myself to the particular means shown.

The work table 26 is connected with the auxiliary guide head 25 by the dove-tailed guide 29 before referred to, and by the 105 means shown for adjusting the table upon the guide frame longitudinally thereon whereby it may be adjusted relatively nearer or farther from the grinding wheel to vary the depth of cut under the control of the 110 pattern. In the particular mechanism here shown, the guide frame 25 is provided with a groove 32^a transversely to the guides 29, and in this is fitted a slide block 32 in which an eccentric 30 is journaled. This eccentric has a journal bearing on axis on the screw stud 31 carried by the work-table 26, as clearly shown in Fig. 1. The eccentric 30 is provided with a lever 39 which is furnished with a pointer traversing the scale 33. When the lever 39 is moved over the scale, it rotates the eccentric 30 about the stud 31, and at the same time shifts the block 32 transversely, but as the block is held against movement to or from the grinding wheel it follows that the work-table 26, the stud 31, and lever 39 move bodily together with the work toward or from the grinding wheel under the adjustment caused by the movement of said lever 39. This form of 115 120 125 130

adjusting device permits of a very slight adjustment of the table 26 upon the auxiliary guide head 25, and at the same time holds it against accidental displacement when adjusted, but I do not confine myself to this particular mechanism for accomplishing this special function. The special object of this small adjustment is to enable the work after being clamped in position to be moved forward to the small extent necessary to enable the grinding wheel to take off just enough cut to provide the proper finished shape. The adjustment is made with each new piece of work clamped in position upon the table 10 for in practice the work in the rough is first clamped in position corresponding exactly to the relative position of the pattern 37 and is then adjusted forward toward the grinding wheel the small distance which is necessary to secure the proper extent of cut upon the casting or other piece of work 28.

It will now be understood that in the grinding operation, the pattern 37 is clamped in position upon the table 35 so that its finished edge projects slightly beyond the table; the lever 39 is thrown to the right (Fig. 2) so that the table 26 is in its normal position farthest away from the grinding wheel and with its forward edge preferably directly above the forward edge of the pattern table 35. When the pattern 37 has been clamped in position, a templet arm 53 is applied to and guided down upon vertical guide 34 on one of the parts 24 of the slide frame 22 until it is in alinement with the pattern. This templet arm 53 is provided with a slotted extension 54 upon which are clamped a plurality of templet fingers 55, said fingers being adjustably clamped in position by any suitable form of clamping devices indicated at 59 (Figs. 4 and 5). These templet fingers 55 are shown as slotted so that they may be moved toward the pattern to contact with it, substantially the same as indicated in Fig. 4, where they are shown in contact with the work 28. After the templet fingers 55 have been once adjusted to the pattern, the templet as a whole is thereafter only employed 50 in connection with the adjustment of the work. In performing this function, the templet is moved upwardly upon the guide 34 to bring the templet fingers 55 to a lever just above the work-table 26, and the work 28 is then adjusted to the fingers and clamped in position by the clamping devices 27, as indicated in Fig. 4. When this is done, the templet may be slipped off the top of the guide 34 during the grinding of 60 the work 28. When a new piece of work is to be applied, the templet is slipped back into position upon the guide 34 to position the new piece of work, and after it has been clamped in position the templet is again re-moved, and so on with each piece of work

so long as the work corresponds to the pattern 37. When the work has been positioned upon the work-table 26, the lever 39 is thrown over to the left (Fig. 2) to the degree required for the extent of cut necessary 70 which will push the work 28 forward to the degree required to insure the proper grinding. The hand wheel 47 is rotated until one edge of the work comes into alinement with the traverse arm 38. The lever 17 is then pulled forward to bring the traverse arm in contact with the pattern 37, and also to bring the grinding wheel 6 into grinding operation with the work 28. The lever is maintained under the pull of the 80 hand so that the transverse arm 38 is maintained in contact with the pattern 37, and at the same time the hand wheel 47 is rotated to move the slide frame 22 transversely. While this action is taking place, 85 the pattern 37 operating upon the traverse arm 38 causes the slide frame 4 to be shifted back and forth corresponding to the irregularities of the pattern, and this operation of the frame 4 carries the grinding 90 wheel 6 forward and backward in a corresponding manner and therefore causes the work 28 to be ground in exact accordance with the shape of the pattern. One complete traversing of the work across the 95 grinding wheel will give the requisite finish, and therefore the operation is both effective and quick. Moreover, it is not possible to perform defective grinding when the provisions of the machine are carefully employed in the manner above described.

In some cases where the operation of the grinding wheel 6 cannot rotate in a plane at right angles to the alinement of the guides 23 and movement of the work, and at the same time insure the grinding of undercut portions, it is essential that the grinding wheel shall be adjusted to an oblique plane, and this is accomplished by rotating the turret head 3 to the proper degree and then 105 clamping it in that position of adjustment. When this is done, the grinding wheel may perform its function in the manner above described and produce undercutting in the work. When the grinding wheel becomes 110 worn and dressed down by the diamond point 56 so that its diameter is materially less than that shown, is is manifest that the traverse arm 38 must be correspondingly adjusted upon the slide head 4; and this is 115 accomplished through the adjustable clamp 40. Otherwise, it would be necessary to provide a new relative adjustment for the work toward the grinding wheel to compensate for its wear, which method would 120 naturally derange the simplicity of the templet means of positioning the work with respect to the grinding wheel, and I therefore prefer to employ the construction in 125 which the traverse arm 38 is adjusted to 130

suit the wearing down of the grinding wheel.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. In a grinding machine, the combination of a main frame, a slide frame adjustably supported thereon with capacity for transverse movement, means movable with said slide frame for supporting work to be ground, a pattern support also carried with the slide frame, means for imparting a transverse reciprocating movement to the slide frame, a grinding wheel, means for supporting and moving the grinding wheel in the plane of its rotation toward and from the work supporting means, and means on the supporting means for the grinding wheel and movable therewith in alinement with the pattern support arranged to traverse a pattern thereon during the transverse movement of the slide frame for controlling the extent of movement of the grinding wheel and its supporting means.

2. In a grinding machine, the combination of a main frame, a slide frame adjustably supported thereon with capacity for transverse movement, means movable with said slide frame for supporting work to be ground, a pattern support also carried with the slide frame, a pattern, detachably clamped upon the support, means for imparting a transverse reciprocating movement to the slide frame, a grinding wheel, means for supporting and moving the grinding wheel in the plane of its rotation toward and from the work supporting means of the slide frame, and adjustable means on the means for supporting and moving the grinding wheel and in alinement with the pattern arranged to traverse the pattern for controlling the extent of movement of the grinding wheel and its supporting means and to compensate for the wearing down of the grinding wheel.

3. In a grinding machine, the combination of a main frame, a slide frame adjustably supported thereon with capacity for transverse movement, means movable with said slide frame for supporting work to be ground, a pattern support also carried with the slide frame, means for imparting a reciprocating movement to the slide frame, a grinding

wheel, means for supporting and moving the grinding wheel toward and from the work supporting means of the slide frame, means on the supporting means for the grinding wheel and movable therewith in alinement with the pattern support arranged to traverse a pattern thereon during the transverse movement of the slide frame for controlling the extent of movement of the grinding wheel and its supporting means, and adjusting devices for adjusting the work supporting means upon the slide frame to or from the grinding wheel relatively with respect to and independently of the pattern support to govern the extent of cut to be made.

4. In a grinding machine, the combination of a main frame, a slide frame adjustably supported thereon with capacity for transverse movement, means movable with said slide frame for supporting work to be ground, a pattern support also carried with the slide frame, means for imparting a reciprocating movement to the slide frame, a grinding wheel, means for supporting and moving the grinding wheel toward and from the work supporting means, means on the supporting means for the grinding wheel and movable therewith in alinement with the pattern support arranged to traverse a pattern thereon during the transverse movement of the slide frame for controlling the extent of movement of the grinding wheel and its supporting means, and a removable adjustable templet guided upon the slide frame so as to be shiftable from a position in alinement with a pattern upon the pattern support into a position to act as a templet to set the work upon the work supporting means.

5. In a grinding machine, the combination of a main frame, a slide frame adjustably supported thereon with capacity for transverse movement, means movable with said slide frame for supporting work to be ground, a pattern support also carried with the slide frame, means for imparting a reciprocating movement to the slide frame, a grinding wheel, means for supporting and moving the grinding wheel toward and from the work supporting means, means on the supporting means for the grinding wheel and movable therewith in alinement with the pattern support arranged to traverse a pattern thereon during the transverse movement of the slide frame for controlling the extent of movement of the grinding wheel and its supporting means, a removable adjustable templet guided upon the slide frame so as to be shiftable from a position in alinement with a pattern upon the pattern support into a position to act as a templet to set the work upon the work supporting means, and adjusting devices for adjusting the work supporting means upon the slide frame to or

- from the grinding wheel relatively with respect to and independently of the pattern support to govern the extent of cut to be made.
5. In a grinding machine, the combination of a main frame, a slide frame adjustably supported thereon with capacity for transverse movement, means movable with said slide frame for supporting work to be ground, a pattern support also carried with the slide frame, means for imparting a reciprocating movement to the slide frame, a grinding wheel, means for supporting and moving the grinding wheel toward and from the work supporting means, means in alignment with the pattern support arranged to traverse a pattern thereon for controlling the extent of movement of the grinding wheel and its supporting means, and means for adjusting the slide frame vertically relatively to the grinding wheel to compensate for varying thicknesses of work to be ground.
10. In a grinding machine, the combination of a main frame, a slide frame adjustably supported thereon with capacity for transverse movement alone, means movable with said slide frame for supporting work to be ground, a pattern support also carried with the slide frame, means for imparting a reciprocating movement to the slide frame, a grinding wheel, means for supporting and moving the grinding wheel toward and from the work supporting means, means in vertical alignment with the plane of the grinding wheel and the pattern support arranged to traverse a pattern thereon for controlling the extent of movement of the grinding wheel and its supporting means, and means for adjusting the grinding wheel and its supporting means together with the means for traversing the pattern to hold the axis of the grinding wheel and said means for traversing the pattern at an angle to the line of adjustment thereof to and from the work supporting means, whereby the plane of the grinding wheel and means for traversing the pattern are obliquely arranged to the line of movement of the slide frame and the work supporting means thereof.
15. In a grinding machine, the combination of a main frame, a transversely reciprocable slide frame having a work support and a pattern support at different elevations one above the other, means to reciprocate the slide frame, a sliding head movable to and from the slide frame, means for reciprocating the head, a grinding wheel carried by the head in substantial horizontal alignment with the pattern support, and a traverse arm also carried by the head in substantial horizontal alignment with the pattern support and a work support, and a
20. In a grinding machine, the combination of a main frame, a transversely reciprocable slide frame having a work support and a pattern support at different elevations, means to reciprocate the slide frame, a sliding head movable to and from the slide frame, means for reciprocating the head, a grinding wheel carried by the head in substantial horizontal alignment with the work support, a traverse arm also carried by the head in substantial horizontal alignment with the pattern support, a pattern detachably clamped upon the pattern support and engaged by the traverse arm, and an adjustable templet means arranged for adjustment to the pattern and acting as a gage for adjusting the work upon its support.
25. In a grinding machine, the combination of a main frame, a transversely reciprocable slide frame having a work support and a pattern support at different elevations, means to reciprocate the slide frame, a sliding head movable to and from the slide frame, means for reciprocating the head, a grinding wheel carried by the head in substantial horizontal alignment with the work support, a traverse arm also carried by the head in substantial horizontal alignment with the pattern support, a pattern detachably clamped upon the pattern support and engaged by the traverse arm, an adjustable templet means arranged for adjustment to the pattern and acting as a gage for adjusting the work upon its support, and adjusting means for the work support whereby it may be adjusted toward the grinding wheel and relatively to the pattern to govern the extent of cut to be given to the work.
30. In a grinding machine, the combination of a main frame, a transversely reciprocable slide frame having a work support and a pattern support at different elevations, means to reciprocate the slide frame, a sliding head movable to and from the slide frame, means for reciprocating the head, a grinding wheel carried by the head in substantial horizontal alignment with the work support, a traverse arm also carried by the head in substantial horizontal alignment with the pattern support, and a turret support for the head for adjusting the angle of the grinding wheel to the work support.
35. In a grinding machine, the combination of a main frame, a transversely reciprocable slide frame having a work support and a pattern support at different elevations, means to reciprocate the slide frame, a sliding head movable to and from the slide frame, means for reciprocating the head, a grinding wheel carried by the head in substantial horizontal alignment with the work support, a traverse arm also carried by the head in substantial horizontal alignment with the pattern support, and a work support for the head for adjusting the angle of the grinding wheel to the work support.
40. In a grinding machine, the combination of a main frame, a slide frame supported thereby and adapted to be reciprocated, means to reciprocate the slide frame, a pattern support and a work support arranged at different elevations and carried by the slide frame said supports being parallel to the plane of movement of said frame, clamping devices for said supports for respectively holding the pattern and work thereon, a slide head supported upon the main frame and capable of reciprocation transversely to the line of movement of the slide frame, means for reciprocating the slide head, a grinding wheel carried by the slide head and arranged in alignment with the pattern support.
45. In a grinding machine, the combination of a main frame, a transversely reciprocable slide frame having a work support and a

the work support so as to be movable to and from the work held thereon, and a traverse arm also carried by the slide head in alinement with the pattern support so as to traverse the pattern held upon said support.

13. In a grinding machine, the combination of a main frame, a slide frame supported thereby and adapted to be reciprocated, means to reciprocate the slide frame, a pattern support and a work support arranged at different elevations and carried by the slide frame said supports being parallel to the plane of movement of said frame, clamping devices for said supports for respectively holding the pattern and work thereon, a slide head supported upon the main frame and capable of reciprocation transversely to the line of movement of the slide frame, means for reciprocating the slide head, a grinding wheel carried by the slide head and arranged in alinement with the work support so as to be movable to and from the work held thereon, a traverse arm also carried by the slide head in alinement with the pattern support so as to traverse the pattern held upon said support, a turret support for the slide head by which the direction of its reciprocation in respect to the direction of movement of the slide frame may be adjusted, and means for holding the turret in adjusted position upon the main frame.

14. In a grinding machine, the combination of a main frame having fixed guides, with a slide frame reciprocable horizontally upon the fixed guides thereon and provided with a work support fixedly secured thereto to move as a unit with the reciprocating slide frame, a grinding wheel, a head supporting the grinding wheel with its axis in horizontal alinement with the work support and freely reciprocable upon the head to move the grinding wheel horizontally to and from the work support during the grinding operation, and manually operable means for reciprocating the head and its grinding wheel whereby the grinding wheel is reciprocated during the grinding operation.

15. In a grinding machine, the combination of a main frame, a slide frame supported thereby and adapted to be reciprocated, means to reciprocate the slide frame, a pattern support and a work support arranged at different elevations and carried by the slide frame said supports being parallel to the plane of movement of said frame, clamping devices for said supports for respectively holding the pattern and work thereon, a slide head supported upon the main frame and capable of reciprocation transversely to the line of movement of the slide frame, means for reciprocating the slide head, a grinding wheel carried by the slide head and arranged in alinement with

the work support so as to be movable to and from the work held thereon, a traverse arm also carried by the slide head in alinement with the pattern support so as to traverse the pattern held upon said support, and hand operable means for adjusting the work support relatively to the pattern and to or from the grinding wheel to determine the extent of cut to be taken off the work.

16. In a grinding machine, the combination of a main frame, a slide frame supported thereby and adapted to be reciprocated, means to reciprocate the slide frame, a pattern support and a work support arranged at different elevations and carried by the slide frame said supports being parallel to the plane of movement of said frame, clamping devices for said supports for respectively holding the pattern and work thereon, a slide head supported upon the main frame and capable of reciprocation transversely to the line of movement of the slide frame, means for reciprocating the slide head, a grinding wheel carried by the slide head and arranged in alinement with the work support so as to be movable to and from the work held thereon, a traverse arm also carried by the slide head in alinement with the pattern support so as to traverse the pattern held upon said support, an adjustable bed for supporting the slide frame whereby it together with its work support may be raised and lowered, adjustable means for raising and lowering the adjustable bed upon the main frame, and locking means for locking the bed in its adjusted position.

17. In a grinding machine, the combination of a main frame, a slide frame supported thereby and adapted to be reciprocated, means to reciprocate the slide frame, a pattern support and a work support arranged at different elevations and carried by the slide frame said supports being parallel to the plane of movement of said frame, clamping devices for said supports for respectively holding the pattern and work thereon, a slide head supported upon the main frame and capable of reciprocation transversely to the line of movement of the slide frame, means for reciprocating the slide head, a grinding wheel carried by the slide head and arranged in alinement with the work support so as to be movable to and from the work held thereon, a traverse arm also carried by the slide head in alinement with the pattern support so as to traverse the pattern held upon said support said slide frame also provided with a guide arranged transversely to the plane of the pattern and work supports, and an adjustable templet adjustably supported by the guide and having fingers said templet adapted to be brought into alinement with the pattern support to engage a pattern thereon for adjustment of the fingers and then be brought

into alignment with the work support to enable the work to be properly adjusted thereon.

18. In a grinding machine, the combination of a main frame having fixed transverse guides, with a slide frame reciprocable upon the fixed guides and provided with a work support, a grinding wheel in alignment with the work support, a head supporting the grinding wheel and reciprocable upon the main frame to move the grinding wheel toward and from the work support, a rotatable turret carried upon the upper part of the main frame and upon which the wheel carrying head is guided to change the angle of the grinding wheel to the work support, manually operated means carried by and movable with the turret for reciprocating the head and grinding wheel, and devices for controlling the extent of movement of the head and grinding wheel comprising devices part of which is secured to the slide and the other to the reciprocating head.

19. The combination of a horizontally reciprocating work support, a rotating grinding wheel, a support for the grinding wheel, means to reciprocate the support and grinding wheel to and from the work support, means to reciprocate the work support,

transversely to the direction of its reciprocation, and means to control the reciprocations of the grinding wheel and its support comprising a pattern and a traverse arm movable over the pattern on the horizontally reciprocating work support. 30

20. The combination of a horizontally reciprocating work support, a rotating grinding wheel, a support for the grinding wheel, means to reciprocate the support and grinding wheel to and from the work support, 40 means to reciprocate the work support across the plane of rotation of the grinding wheel, means to control the reciprocations of the grinding wheel and its support comprising a pattern and a traverse arm movable over the pattern, and hand adjusting means for adjusting the work support transversely to its reciprocating movement independently of the pattern to regulate the extent of cut on the horizontally reciprocating work support. 45

In testimony of which invention, I hereunto set my hand.
